(57) **CLAIM**

The ornamental design for a viewer portion of game piece, as shown and described.

DESCRIPTION

FIG. 1 is a first top perspective view of a viewer portion of a game piece showing our new design.

FIG. 2 is a second top perspective view thereof.

FIG. 3 is a top plan view thereof.

FIG. 4 is a bottom plan view thereof.

FIG. 5 is a left side elevational view thereof, the right side elevational view being a mirror image thereto.

FIG. 6 is a front side elevational view thereof, the rear side elevational view being a mirror image thereto.

FIG. 7 is a first top perspective view of a second embodiment thereof.

FIG. 8 is second top perspective view thereof; and,

FIG. 9 is a top plan view thereof.

The broken lines are for illustrative purposes only and form no part of the claimed design.
